ABSTRACT OF THE DISCLOSURE

A process for producing a polynitrile from an aromatic hydrocarbon containing at least two alkyl substituent groups, the alkyl group having 1-3 carbon atoms, wherein the hydrocarbon is contacted in the gaseous phase with ammonia in the presence of an oxide catalyst at a temperature of 400-500° C., a contact time of 0.01-30 seconds and a catalyst-on-stream time of less than 30 minutes. The process is particularly applicable to producing terephthalonitrile from p-xylene.

This invention has to do with a process for forming aromatic polynitriles, particularly for forming terephthalonitrile from p-xylene.

Catalytic conversion of hydrocarbons and ammonia to nitriles has received considerable attention in recent years. For example, toluene has been converted to benzonitrile in the presence of ammoniation catalysts such as associations of molybdena and vanadia. However, while conversion of xylenes to the corresponding tolunitriles has been accomplished with reasonable success, conversion of tolunitriles to the corresponding dinitriles has been unsatisfactory.

In prior processes, temperatures as high as about 700° C. have been required. At such temperatures, there has been a rapid loss in catalyst activity, decrease in conversion selectivity and substantial coke formation on the catalyst, all cooperating to reduce the yield of desired product.

Another process has also been developed recently for producing nitriles. This is generally referred to as "ammonoxidation," wherein oxygen is used as a charge material with hydrocarbon and ammonia. Typical of ammonoxidation catalysts are associations of bismuth oxide and molybdena. With oxygen, as in the form of air, oxygenated products are formed, making necessary a purification system to effect separation of desired nitrile and oxygenated contaminants.

Since aromatic polynitriles such as phthalonitrile and terephthalonitrile are of value, for example, in the dye-stuff and fiber industries, respectively, it would be advantageous to have available an efficient and effective process for converting xylenes to aromatic polynitriles. The present invention is directed to just such a process.

It is an object of the present invention, therefore, to provide a selective catalytic process for forming aromatic polynitriles. Another object is to provide such a process substantially free from coke formation. Still another object is to provide such a process in which temperatures lower than conventional ammoniation temperatures are employed. A further object is to provide an effective process substantially free from formation of undesired oxygenated products. Another object is to provide a continuous process so characterized. A more specific object is to provide a process for converting xylenes to the corresponding dinitriles, and particularly to terephthalonitrile. Other objects will be apparent from the following description.

2

In accordance with the present invention, there is provided a process for preparing aromatic polynitriles, comprising: contacting an aromatic hydrocarbon with ammonia, in gaseous phase, at a temperature from about 400° C. to about 500° C. in the presence of an oxide catalyst, with a contact time of from about 0.01 second to about 30 seconds and a catalyst-on-stream time of less than about 30 minutes. The aromatic hydrocarbon is one which is: stable to thermal decomposition, in the vapor phase at said reaction conditions, and represent by the general formula

Ar—R_n

wherein Ar is an arylene group, R is an alkyl group having from 1 to 3 carbon atoms, and n is a small whole number, at least 2.

Aromatic hydrocarbons useful herein include: xylenes; tri-, tetra-, penta- and hexa-methyl benzenes; diethyl and related polyethyl benzenes; polypropyl benzenes; di- and further-methylated, -ethylated, and -propylated naphthalenes anthracenes, etc. Preferred herein are xylenes and, particularly, p-xylene. Thus, the arylene group can be a benzene, naphthalene, anthracene, etc. ring.

As indicated above, the catalysts used herein include those known as ammoniation catalysts, that is, catalysts used in the conversion of hydrocarbons and ammonia to nitriles without substantial addition of oxygen to the reaction charge. Such catalysts include associations or mixed oxides of molybdenum and/or tungsten, and of vanadium, iron and/or cobalt. Molybdena/vanadia catalysts are effective catalysts in the process of this invention.

Ammonoxidation catalysts can also be used in the present process although a free oxygen-containing gas is not used as a charge material. Typical of such catalysts are the bismuth oxide/molybdena catalysts referred to above.

In addition to such catalysts, I have also found that the following can be used:

associations of molybdena and ferric oxide, as

Fe₂O₃Mo₆O₁₈,

associations of stannic oxide and vanadia, H₄SiMo₁₂O₄₀, Bi₄O₆(H₄SiMoO₄₀), and Bi₃O_{4.5}(H₃PMo₁₂O₄₀).

The catalyst can be used per se, or can be supported on or mixed with an inert support such as Carborundum, pumice, clay or the like, in which case texture, surface area and pore diameter can be suitably controlled. The inert support can serve to provide mechanical strength and abrasion resistance to the catalyst. The catalyst, with or without support, can be in the form of fine particles such as suitable for use in a so-called "fluidized" reactor bed, pellets, granules, etc.

Essential features in the formation of the aromatic polynitriles are contact time and catalyst-on-stream time. Contact time is the period of time during which a unit volume of the reactants is in contact with a unit volume of catalyst. Catalyst-on-stream time is the time during which the catalyst is in use in converting an aromatic hydrocarbon and ammonia to the desired polynitrile, before it is reactivated or regenerated. It has been found that the contact time should be from about 0.01 second to about 30 seconds, preferably 0.1-10 seconds, with a catalyst-on-stream of less than about 30 minutes, preferably less than 10 minutes.

In prior processes brief contact times of the order of those used herein have been employed; however, catalysts have been maintained on stream for several hours before reactivation or regeneration. In such processes, aromatic mononitriles have been formed, with little or no formation of polynitriles. Additionally, the much longer on-stream times at elevated temperatures have resulted

in substantial coke formation on the catalyst. Removal of the coke by burning the same with oxygen has interfered with the heat balance of the process and, in some instances, has resulted in damage to the catalyst.

In the presence of ammonia and hydrocarbon, mixed oxide catalysts of transition metals are reduced. The reduced form is considerably less active than a more oxidized form, which need not necessarily be the highest oxidation level of the oxide catalyst.

In the present process, the relatively short catalyst-on-stream times make possible maintenance of a high catalytic level, also avoiding any substantial coke deposit on the catalyst. Reactivation of the catalyst with a free-oxygen containing gas such as air or oxygen can be accomplished readily, therefore, in a briefer period of time than in the prior processes alluded to above. In reactivating a used catalyst, it is advantageous to use a sufficient quantity of oxygen to convert the used catalyst to an oxidized state.

In the present process, an excess of ammonia is generally used in relation to the stoichiometrical quantity of aromatic hydrocarbon. However, from about 0.5:1 to about 12:1 volumes of ammonia can be used per volume of xylene, especially ratios of about 1:1 to 6:1. It will be understood that larger ratios of ammonia to hydrocarbon are used as an Ar group is more substituted with R groups than is the benzene ring substituted with methyl groups to form xylenes. It is economical, however, not to use a large excess of ammonia or of an aromatic hydrocarbon, particularly in a continuous operation such as described below in order to simplify recycling of a reactant.

The aromatic hydrocarbon reactant can be used per se or can be present in admixture with other hydrocarbons inert in the reaction, such as paraffin or benzene. Preferably, the reaction system is diluted with an inert gas such as nitrogen, steam or water vapor. Thus, it has been found that the use of steam or water vapor has the advantage of retaining the catalyst oxygen for a longer period of time than when the aromatic hydrocarbon is converted in the substantial absence of added steam or water vapor. Preferably, from about 3 to about 10, and especially about 5 volumes of steam are used per volume of total reactants, namely, aromatic hydrocarbon and ammonia.

The use of a diluent in the process of this invention is advantageous in several respects. With a diluent, the process is operated with a net production of hydrogen and no net heat generation. The diluent also serves to: carry off process heat thereby obviating the need for internal heat transfer surface, and diminish the partial pressures of the reducing compounds charged and formed.

Reacting temperature for forming a polynitrile is an important feature. Temperatures below about 400° C. are to be avoided since yields are insufficient. Temperatures above about 500° C. are also to be avoided, since yields are reduced by virtue of decomposition of reactants and products. Preferably, temperatures of the order of 450-460° C. are employed.

Reaction pressures generally range from about 1 to about 10 atmospheres, absolute. Pressures of 1.5-2 atmospheres, absolute, are preferred.

The process can be conducted intermittently or continuously, with the latter preferred. The latter is particularly advantageous and is illustrated generally in the accompanying drawing which constitutes a schematic flow diagram. In the drawing, for example, p-xylene in line 10 and ammonia in line 11 are mixed in line 12 and are charged to reactor 13, wherein they are in reaction in the presence of a catalyst introduced into 13 from line 14. Reactor 13 can comprise a lower preheating zone and an upper reaction zone. Catalyst and reactants flow concurrently up through reactor 13, with catalyst being removed through line 15 to an upper portion of reactor or regenerator 16. Air or other suitable active oxy-

gen-containing gas is introduced from line 17 to a lower portion of regenerator 16 and is in countercurrent contact with the catalyst for reactivation. Gases formed during reactivation, broadly termed "flue gas," are removed through line 18. Reactivated catalyst is recycled from 16 through line 14 to reactor 13. As shown, make-up catalyst can be added to line 14 from line 19, and catalyst fines or catalyst rejected for any reason can be removed through line 20.

Reaction products comprising terephthalonitrile, tolnitrile, hydrogen and water, together with unreacted ammonia, are removed from reactor 13 through line 21 to separator 22, from which the nitriles are discharged through line 23. Terephthalonitrile and tolunitrile can be separated from one another and tolunitrile can be recycled (not shown) with the hydrocarbon in line 10. Hydrogen, water and ammonia are removed from 22 through line 24 to hydrogen separator 25. Hydrogen is removed from 25 via line 26. Ammonia and water are taken from separator 25 through line 27 and can be passed through line 28 to line 12 for use in reactor 13 or can be passed through line 29 to ammonia recovery unit 30. Ammonia is removed from unit 30 through line 31 and is combined with ammonia charge in line 11. Water is removed from unit 30 through line 32. Diluent can also be charged through line 33.

During reactivation or regeneration of the catalyst, as in unit 16 of the drawing, the temperature should be controlled lest the catalyst be damaged. The maximum temperature to be used will vary with catalysts employed. Air is preferred as an oxidation medium; however, oxygen and other free oxygen-containing gas can be used satisfactorily.

The following typical, and non-limiting, examples illustrate the invention.

EXAMPLE 1

A series of runs was conducted with p-xylene, ammonia and a molybdena/vanadia catalyst formed by the following procedure.

To a slurry of 187 grams of vanadia in 700 ml. of distilled water, heated on a hot plate to 80° C., was slowly added 379 g. of oxalic acid dihydrate. The solution turned blue and carbon dioxide escaped while vanadia dissolved with formation of vanadyl oxalate:

After all the vanadia had gone into solution, 181 g. of ammonia molybdate in 500 ml. of distilled water was added slowly with agitation. A black color developed but no precipitate formed. The pH of the combined solutions was 1.6. It was raised to 6.3 by the gradual addition of concentrated aqueous ammonia (190 ml.). After addition of about 100 ml. of ammonia, the pH had increased to about 4.4, and a black precipitate was formed. When at this value agitation was stopped, the entire mass in the reaction vessel used solidified due to the formation of a metastable micel structure. The mass could be liquified again upon continuing the agitation. The slurry was poured into baking dishes and left overnight. Evaporation of the aqueous phase was done very slowly; during 5 days, the temperature was brought up gradually to 100° C., and so maintained for 24 hours. Finally, the catalyst was calcined in a muffle furnace. The temperature of the muffle furnace was brought in 3½ hours from 40° C. to 400° C., and kept at 400° C. for one hour. The catalyst mass was then cooled and broken in pieces. The fraction of 6-9 mesh was used for the series of runs.

All runs were carried out with the same catalyst charge comprising 123.2 grams (200 ml.) of the molybdena/vanadia catalyst in a process scheme such as shown in the drawing. Product was accumulated during 30 minute periods and was designated Sample A; then, for one or two subsequent 30 minute periods, product was also accumulated and designated Samples B and C, respectively. The

catalyst was reactivated with air after each B run of a series of A and B runs, or after a C run in a series of A-B-C runs.

The reaction effluent was trapped in two cooled flasks. Terephthalonitrile (TPN), formed as a product, is wholly insoluble in xylene; the product crystals were filtered, washed with hexane, dried and weighed. The mother liquor and hexane washings were combined and analyzed for tolunitrile (TN) by gas chromatography. The results are shown in Table 1 following.

In Table 1, x/a represents the mole fraction of p-xylene converted to p-tolunitrile and y/a represents the mole fraction of p-xylene converted to terephthalonitrile.

approximately 20 parts of terephthalonitrile are produced per 1000 parts by weight of catalyst.

EXAMPLE 3

Example 2 was repeated except that the molar feed ratio p-xylene/ammonia/water was 1/3/42 and the p-xylene contact time was 2.4 seconds. The catalyst-on-stream time was about 30 minutes. Nearly 30 parts by weight of terephthalonitrile were produced per 1000 parts by weight of catalyst before the latter lost its ability to aid in the formation of the dinitrile. The introduction of steam more than tripled the catalyst life, increased reaction rate, and reduced the ammonia recycle by over ten fold.

(A = first half hour, B = second half hour, C = third half hour)

The results shown in Table 1 reveal that conversion of p-xylene to terephthalonitrile is substantially greater during an initial 30 minute run, than during a subsequent 40 30 minute run. For example, in Run 76A, the mole conversion is 39 percent; whereas, in Run 76B, it is only 7 percent. The same pattern is revealed for A and B of Runs 77 through 83, inclusive. The data indicate that the catalyst is reduced in activity with respect to formation of terephthalonitrile, but has greater activity for the production of tolunitrile. This is due to oxygen loss of the catalyst.

With very short contact times, the catalyst activity can be maintained for relatively longer on-stream times but conversion is meager and uneconomical. If contact time is very short, catalyst-on-stream time can be extended even beyond about 30 minutes, but the results are similarly uneconomical. With longer contact times, as 5-30 seconds, catalyst-on-stream time is of shorter duration but conversion of aromatic hydrocarbon to desired polynitrile is higher. For example, it is to be understood that catalysts employed herein differ in activity. Thus, contact times of 5-30 seconds are preferred when using $\text{Fe}_2\text{O}_3\text{Mo}_6\text{O}_{18}$, rather than briefer contact times.

EXAMPLE 2

A mixture of p-xylene and ammonia was passed downwardly through a static bed of the molybdena/vanadia catalyst described in Example 1, at 460° C. at a contact time of about 3 seconds. During the first 10 minute period, the product was predominantly terephthalonitrile. Then, a mixture of terephthalonitrile and tolunitrile was formed. Finally, after about one hour, substantially only tolunitrile was formed. When about 30 moles of ammonia are charged per mole of p-xylene, about 8 parts by weight of terephthalonitrile are produced per 1000 parts by weight of catalyst. When, however, part of the ammonia is replaced by nitrogen diluent such that the mole ratio p-xylene/ammonia/N₂ is 1/3/30 and the same contact time and the same on-stream time are employed,

It will be evident from the foregoing that an effective process has been found for the production of aromatic polynitriles. Terephthalonitrile, for example, is formed from p-xylene and can be used for the formation of terephthalic acid, which is of importance in the manufacture of synthetic fibers. Phthalonitrile can be formed from o-xylene, and can be used in the formation of phthalocyanine dyes. Other uses will be evident to those familiar with the art.

Many modifications and variations of the invention as set forth above may be made without departing from the spirit and scope thereof. Consequently, the appended claims are intended to include such modifications and variations.

I claim:

1. In the production of an aromatic nitrile by contacting ammonia with an aromatic hydrocarbon in the gaseous phase, in the presence of an oxidized form of an oxide catalyst selected from the group consisting of ammoniation catalysts and ammonoxidation catalysts, the aromatic hydrocarbon being selected from the group consisting of alkyl substituted benzene, alkyl substituted naphthalene and alkyl substituted anthracene wherein the alkyl group has 1-3 carbon atoms and there are at least two alkyl substituent groups, the improvement for producing aromatic polynitriles comprising: effecting said contacting of ammonia, aromatic hydrocarbon and catalyst in the absence of molecular oxygen at a temperature from about 400° C. to about 500° C., a contact time of from about 0.01 second to about 30 seconds and a catalyst on-stream time of no longer than about 30 minutes, followed by removal of said catalyst from on-stream, contact of the said removed catalyst with a molecular oxygen-containing gas to regenerate the same and recycling said regenerated catalyst to the on-stream.

2. The process defined by claim 1 wherein the aromatic hydrocarbon is a xylene.

3. The process as defined in claim 1 wherein the aromatic hydrocarbon is p-xylene.
4. The process defined by claim 1 wherein the catalyst-on-stream time is from about 0.01 second to about 10 minutes.
5. The process defined by claim 1 wherein the contact time is from about 0.1 second to about 10 seconds.
6. The process defined by claim 1 wherein the contact time is from about 0.1 second to about 10 seconds and the catalyst-on-stream time is from about 0.1 second to about 10 minutes.
7. The process defined by claim 1 wherein the temperature is from about 450° C. to about 460° C.
